United States Patent Office.

HIRAM B. TRIPP, OF BOSTON, MASSACHUSETTS.

Letters Patent No. 104,666, dated June 21, 1870.

IMPROVEMENT IN BOLTS FOR SAFE-DOORS.

The Schedule referred to in these Letters Patent and making part of the same.

To all persons to whom these presents shall come:

Be it known that I, HIRAM B. TRIPP, of Boston, county of Suffolk and State of Massachusetts, have invented certain new and useful Improvements in Bolt-Connections; and that the following is a full and exact description of the same, reference being had to the accompanying drawing.

The present invention relates more particularly to that class of locks for safes, vaults, &c., for the deposit of valuables, in which two handles are provided, the one for operating the locking mechanism, and the other for throwing the bolts, and the principal object of the invention is to insure and obtain greater safety and security against the throw of the bolts, even should the lock be forced from the door.

The principle of the invention is in a disposition of mechanism between the locking-devices and the handle for throwing the bolts, to be actuated by the lock, to make a connection between the bolt-handle and the bolts before they can be thrown or operated by their handle.

This invention consists in the combination and construction of certain parts with a lever, pivoted to the bolts, either one or more, and moving therewith, and connected with the locking-devices, to be actuated thereby in such a manner as to establish a connection through the said lever and parts, and the handle for throwing the bolts so that, by then turning the handle in the proper direction, the bolts can be thrown either in or out, as the case may be.

In the accompanying drawing my improvements in bolt-connections for locks are illustrated.

In Plate 1, Figure 1 is a view, in elevation, of a locking mechanism, bolts, and of connecting devices between the two, arranged in accordance with this invention.

Figure 2 is a transverse vertical section, taken in plane of the line $x x$, fig. 1.

In Plate 2, Figure 3 is a view in elevation, showing two graduated dials or disks, the one for the setting of the lock-tumblers and the other for the setting of the tumblers connected with bolt-handle.

Figure 4 is a horizontal section in plane of line $y y$, fig. 1, plate 1.

A, in the drawing, represents a frame, in and to which, by hinges, a door, B, is hung, for being opened and closed.

C, a box or case, applied to inside of door; the back plate, to this box is shown as removed, exposing the interior to view.

D, a series of rotating tumblers or disks, arranged within the box C, and connected with the spindle to knob or handle E, having graduated dial on outside of door, by and through which such tumblers are brought into the proper position to allow the connection shown

at F, with the latch-lever F², to be made, so that, then properly turning the handle, the block G will be swung on its pivot or center a.

The arrangement of rotating tumblers D with the latch-lever and block, just above referred to, is substantially the same as that of the well-known "Sergeant Combination-Lock," and the said several parts, in the setting and upsetting of the tumblers, &c., operate similar thereto, and therefore it is not deemed necessary to herein more particularly describe them, they forming in themselves no part of this invention.

H, a stem hung to block G of the "Sergeant lock," so that, in the movement of the said block through the latch-piece F², as described, said stem will have a motion into and out from, as the case may be, the axis of the tumblers.

This stem H projects through one end of the lock-case C, and has a nut, I, in its extreme outer end.

K, a lever, hung upon a fulcrum, at b, of a standard, L, secured by screws to the lower bolt M of two bolts M M, arranged in parallel horizontal planes, one above and the other below the lock-case, and to move in and through parallel vertical guide-rails N, attached to the inside of the door.

The two bolts M M are connected by a tie-plate, O, so as to move together.

The lever K, above referred to, is constructed with an upright arm, P, made at its extreme outer end, of a hook-form, c, partially encircling the stem H, and of two horizontal arms Q and R, extending partially along the length of the lower bolt M, and just above the same.

The horizontal arm R to lever K has, near its outer end, a standard, S, to which is fixed a horizontal arm, T, projecting by its length across the periphery of a series of rotating tumblers or disks U, arranged at and upon the spindle and shaft V of the handle W, provided for throwing the bolts M.

These tumblers are located behind the plate X, between it and the inside of the door, and each tumbler is in itself constructed with a notch or opening, Y, into its periphery, and in other respects similar to the rotating tumblers of combination-locks, and are set and unset through the bolt-handle W, with its graduated dials, in a similar manner to the Sergeant or other combination-locks.

Through the lever K, above referred to as hung to the bolts, connection must be established between the bolts and the bolt-handle W, before they can be thrown by the handle.

To do this, it is necessary to set the rotating tumblers, connected with bolt-handle, so as to have the opening or notches Y thereto opposite and in position, as shown at Z, fig. 1, just above the standard S to lever K, and also to set the rotating tumblers of the

lock-box C, when, through the handle to such tumblers, establish the connection of the latch-piece F² shown at F.

By now turning said lock-handle in the proper direction through the stem H, connected with the block G thereof, the lever K is turned on its fulcrum at b, carrying its standard S and arm T beyond the peripheries of the tumblers on bolt-handle into the notches Y, which thus establishes a connection between the bolts and the bolt-handle, so that, in then turning the bolt-handle, the bolts will be thrown, moving together and as one, and either in or out, as the case may be.

Throwing off the lock-latch piece, by turning the lock-handle in the proper direction, the lever K is left free, and, by the action of the bent spring A², is moved out of connection with the tumblers of bolt-handle, so that, with their combination destroyed, it is, as is obvious, impossible to make a connection of the bolt-handle with the bolts, even should the lock-tumblers be properly set, as in such case the standard S to connection-lever K, if the lock-handle be turned to move the same, would abut against the peripheries of the tumblers, establishing no connection.

The upper part B² of the vertical arm to connection-lever K is hinged or pivoted to the main portion, which is extended at d, along the part B², forming a bearing therefor on one side. The object of this construction is to prevent injury to the locking mechanism as the bolts are operated, said hinged part B², when the connection-lever K is moved by the action of the bolt-handle to draw in the bolts, yielding or giving to the force thereof against a fixed collar or nut, C², on the stem connected with locking-devices, thus obviating concussion or jar to the inside of the lock. h² a vertical lever, hung up on a fulcrum at f, of the door, from which it extends upward and downward, connecting with the nut C² to stem H by its forked upper end, and by its lower end to and with a slide-bar, Y², that is slotted at its end, where hung by pins l to the said lever, and at its other end is arranged to slide within the seat or rest W², fixed to the door in position to support the connection-lever K at a point just below the bolt-tumblers.

With this lever-connection between the slide-bar, as the stem is actuated to throw the connection-lever K into connection with the bolt-handle, said slide-bar, at the proper time, through the movement of the said stem, and just previous to the completion of its full movement, is slid on the rest, bringing its tongue-piece

g just beyond the edge b of rest, and into position to serve as a rest and bearing to the tail-piece i of connection-lever K, as in the turning of the bolt-handle the bolts are thrown from time to time.

In lieu of arranging the bolt-tumblers directly on the spindle to bolt-handle, they may be on an independent spindle, and a connection between the two spindles made through gearing; and, also, it is obvious that the action and movement of the connection-lever K is not dependent on the use of tumblers to bolt-handle, but with tumblers, located to be set by the bolt-handle, as described, double security is obtained, and the throwing of the bolts rendered, to the uninitiated, the more complex and embarrassing.

Various forms of locks for operating the connection-lever may be employed, and either of the class known as "combination-locks," or of any other class, and, in fact, with a locking mechanism attached to or connected with the bolt-handle, for operation substantially as described, it is not absolutely necessary, although it is preferable, to have locking devices for actuating the connection-lever K or its equivalent.

Having described my invention, What I claim, and desire to secure by Letters Patent, is—

1. The lever K, pivoted to bolt M, in combination with the stem H and the lock-handle, the bolt-handle, and their locking-tumblers, substantially as and for the purpose described.
2. The armed lever K, formed with tail-piece i and hinged part B², in combination with the slide Y² and stem H, substantially as and for the purpose described.
3. The stem H, provided with nuts I C², in combination with the hinged part B² of the lever K and with the lever Z², both playing on the stem between the nuts, and operating, in combination with the slide Y², substantially as described.
4. The slide Y², having at one end the tongue-piece h, and moving on the rest W², in combination with the lever K, formed with tail-piece i, and with the pivoted lever Z² hinged at the other end, substantially as and for the purpose described.

The above specification of my improvements in bolt-connections signed by me this 28th day of March, A. D. 1870.

H. B. TRIPP.
